UNITED STATES PATENT OFFICE.

CHARLES W. KENNON, OF TAMPA, FLORIDA, ASSIGNOR TO KENNON CINDER GUARD CO., INCORPORATED, OF TAMPA, FLORIDA, A CORPORATION OF DELAWARE.

GUARD FOR CAR-WINDOWS.

1,114,365.

Specification of Letters Patent.

Patented Oct. 20, 1914.

Application filed October 3, 1913. Serial No. 793,164.

To all whom it may concern:

Be it known that I, CHARLES W. KENNON, a citizen of the United States, residing at Tampa, in the county of Hillsboro and State 5 of Florida, have invented certain new and useful Improvements in Guards for Car-Windows; and I do hereby declare the following to be a full, clear, and exact description of the invention, such as will enable 10 others skilled in the art to which it appertains to make and use the same.

The present invention relates to guards for car windows, and has for its purpose to provide a device of that character which 15 will effectively prevent the entrance of cinders and smoke into the car when the windows are opened, and thus avoid the attendant discomfort to passengers, and other well known disagreeable results.

20 A further purpose of the invention is to provide a window guard which will serve as a means for causing a constant draft of fresh air to enter the car while the car is moving; and one which is simple in construction and will not appreciably interfere with the range of vision of the person sitting at the car window.

With these and other objects in view the invention consists in the novel details of 30 construction and combinations of parts more fully hereinafter disclosed and particularly pointed out in the claims.

In the accompanying drawings forming a part of this application, and in which similar reference symbols indicate corresponding parts in the several views: Figure 1 illustrates the application of the device to a car window. Fig. 2 is a front elevation of the guard removed; and Fig. 3 is a top plan 40 view of the same.

Referring to the construction in detail, the device consists of a curved sheet metal plate 1 and a similarly curved plate 2 of less width than the plate 1, and both of said 45 plates are flared outwardly, as clearly shown in Figs. 1 and 2. The plate 1 is provided with transverse reinforcing strips 3, and a longitudinally disposed strip 4 secured along its inner side edge by rivets 5, or in any 50 other suitable manner. The outer edge of the plate 1 is reinforced by folding upon itself, as at 6, and the outer and inner edges of the plate 2 are similarly strengthened by the folds 7 and 8, respectively.

55 The two plates 1 and 2 are disposed in

relatively angular relation and secured to each other through the medium of a plurality of spacing members 9, whose respective ends 10 and 11 are secured by engaging under the strips 3 and passing through 60 suitable openings formed in the plate 2, and against which the divided free ends are turned, as clearly shown in Fig. 2. A pair of connecting and spacing members 9^a is secured to the plates 1 and 2, at the extreme 65 ends, by passing therethrough and folding over their edges. The adjacent outer edges of the plates are secured at either end by the spacing members 12, which are fastened to said strips in a manner similar to the members 9, or in any other preferred way. By 70 thus connecting the inner and outer plates the relatively wide opening X is provided for directing a strong current of air into the space between the plates and carrying the 75 cinders and smoke from the engine, and the curved surface of the plate 1 deflects the same outwardly through the narrow opening Y between the adjacent edges, as shown in Fig. 3. Said outlet opening Y is covered 80 by a screened strip 13, that is secured by the inturned edges 6 and 7 of the plates. The cinders which are collected between the plates fall through the open space at the bottom edges, and are thus released at a 85 point sufficiently removed from the open window to prevent their entrance into the car. In some instances it may be desired to omit the screened strip, in which event the blast of air issuing through the opening 90 Y would carry away the cinders, but the use of the screen, as shown in the present instance, is preferred.

The guard is adapted to be mounted in a vertical position immediately in front of the window, as shown in Fig. 1, and in this position is detachably secured by means of a number of thumb bolts 14 passing through slots 15 and having locking and unlocking positions after the usual manner.

In operation, the moving car causes a strong blast of air through the outlet opening Y, and this blast is directed from the window in such a manner as to produce a draft of air through the window from within the car, and thus cause a continuous circulation of air for the car's ventilation.

It is obvious that those skilled in the art may vary the details of construction and arrangement of parts without departing 110

from the spirit of my invention, and therefore I do not wish to be limited to such features except as may be required by the claims.

5 I claim:—

1. In a guard for car windows, the combination of a pair of members disposed in spaced and relatively angular relation providing an inlet and an outlet opening, and 10 leaving open upper and lower ends formed by the upper and lower edges of the two members; a screen covering said outlet opening; and means for securing the guard to the car window, substantially as described.
2. In a guard for car windows, the combination of a pair of curved plates of relatively different widths; members securing said plates together to provide a broad inlet opening and a relatively narrow outlet opening, and leaving open upper and lower ends formed by the upper and lower edges of the two members; a screen covering said outlet opening; and means on one of said 25 plates for securing the guard to the car window, substantially as described.

3. The combination with a car window, of a guard therefor comprising a curved plate disposed vertically against the window and projecting outwardly therefrom;

a second curved plate secured to the first-named curved plate and providing therewith a broad inlet opening and a relatively narrow outlet opening, and leaving open upper and lower ends between the plates 35 formed by the upper and lower edges of said plates; and a screen covering said outlet opening, substantially as described.

4. The combination with a car window, of a guard therefor comprising a curved plate 40 disposed vertically against the window and projecting outwardly therefrom; a second curved plate of less width than the first curved plate; members securing said plates in spaced relation providing a broad inlet 45 opening and a relatively narrow outlet opening, and leaving open upper and lower ends between the plates formed by the upper and lower edges of said plates, the edges of said plates adjacent said outlet opening being 50 turned inwardly; and a screen strip secured to said turned-in edges and covering said outlet opening, substantially as described.

In testimony whereof, I affix my signature, in presence of two witnesses.

CHARLES W. KENNON
